DESIGN FOR AN ELECTRIC INSECT TRAP

Corliss L. Crawford, Pomona, Calif.

Application September 4, 1940, Serial No. 94,808

Term of patent 7 years

To all whom it may concern:

Be it known that I, Corliss L. Crawford, a citizen of the United States, residing in Pomona, in the county of Los Angeles and State of California, have invented a new, original, and ornamental Design for an Electric Insect Trap, of which the following is a specification, reference being had to the accompanying drawing, forming part thereof.

Fig. 1 is a top plan view of an electric insect trap, showing my new design.

Fig. 2 is a perspective view taken from the left side as indicated by the numerals 2—2 in Fig. 1.

Fig. 3 is an end elevation taken along the line 3—3 in Fig. 1.

Fig. 4 is a cross-sectional view taken along the line 4—4 in Fig. 1.

I claim:

The ornamental design for an electric insect trap, as shown.

CORLISS L. CRAWFORD.
